UNITED STATES PATENT OFFICE.

JOHN H. TAYLOR, OF PEORIA, ILLINOIS.

CAR COUPLING.

Application filed May 15, 1925. Serial No. 30,413.

This invention has reference to car couplers, having for its object to provide a structure in a coupling that will be exceedingly simple and readily manufactured at low cost; one that is very strong, and above all a structure wherein the knuckle will hold the connected relation of cars even through the coupling pin, or rather that pin used as a pivot for the knuckle, **may be broken or removed.**

To the end that the invention may be thoroughly understood I have provided the accompanying drawing wherein:

Figure 1 is a plan of my improved car coupling showing certain parts in section.

Figure 2 is a longitudinal sectional elevation of the same.

Figure 3 is an elevation of the coupler-head in transverse section on line 3—3, Figure 1, and

Figure 4 shows a knuckle in perspective as I construct it.

The coupler-head is denoted at 1 and includes the usual stem 2 for attachment to the car, not shown, and has a cavity 3 in the lower portion for receiving a knuckle 4 and a locking member to be described, there being a further cavity 6 forming a guideway for receiving the said locking member, and communicating with said cavity 3, the same extending at right angles to the plane of swinging movement of the said knuckle 4.

The said knuckle as shown in Figures 1 and 4 includes at one side of its point of pivotal mounting the jaw 4' which is limited in its movement in one direction by a stop 4² which meets a lug 1' of said head 1. It also has a portion 4³ at the other side of the pivot point which includes a toe 4⁴ disposed substantially at right angles to the general length of said portion 4³. Below said toe 4⁴ the said portion 4³ is undercut at 7 by sloping away from said toe toward the opposite side of the knuckle from which said toe extends as most clearly shown in Figure 3.

The locking member previously referred to is best shown in Figure 3. It is a single piece structure including a top yoke-portion 5 and two depending spaced extensions 8 and 9. The extension 8 lies normally guided by the walls of the head 1 within the cavity 6 referred to. The extension 9 has a foot portion 9' angled downwardly in the general direction of the extension 8 and normally rests in a socket 10 as a further extension of said cavity 6 and below the cavity 3.

Beneath said foot portion and as a part thereof is a lug 11 with which engages one arm of a bell-crank-lever 12 pivotally carried by a pin 13 extending into the said head 60

1. To the other arm of the lever 12 is attached a rod 14 or equivalent part by which said lever may be operated to raise the locking member 5, 8, 9 out of its seat. The upper side of the described foot portion is an 65 upwardly angled surface and is adapted in its raising movement to engage the undercut portion 7 of the knuckle and to thereby cause the latter to be swung about the pin 15 forming its pivot in said head 1.

The coupling position of the knuckle is shown in Figure 1 wherein its toe 4⁴ engages behind the inner or rear side of the extension 9, being held in that position by the engagement of the extension 8 with the portion 4³ as may be clearly seen in Figures 1 and 3.

The pull applied upon the jaw 4² by its connection with the companion coupling of a car, neither of which is shown, tends to swing the knuckle about its pivot but the extension 8, of course, prevents such movement, the said pull upon the jaw being transferred to the said pin 15 and to the locking member 5, 8, 9 through the extension 9 of the latter and the toe 4⁴.

Since the yoke-portion 5 of the locking member and the extension 9 thereof lie behind the abutment of the head 1 by creating the cavity 6, and since, also, the foot-portion 9' lies in the socket 10, said locking member cannot yield to the strain or strains imposed thereon and it may be seen that even though the pin 15 were to be removed, or were broken, the toe 4⁴ would still maintain 95 the coupled relation.

The relation of the parts is such that when desired to cause uncoupling by swinging back the jaw 4' the lever 12 is operated to lift the member 5, 8, 9, or the latter may 100 be lifted by hand. This action first raises the extension 8 above the level of the top surface of the knuckle, there being permitted a sufficient movement of the said member 5, 8, 9 for this purpose before the 105 foot 9' engages the sloping undercut surface of the said knuckle, the continued movement, however, swinging the latter to its outward limit sufficient for the jaw 4' to release or receive a companion jaw, not 110 shown. When the jaw 4' lies at its outermost position or that where the companion

coupling can enter or pass the same, the limit of outward movement being secured by contact of the stop 4² and lug 1', the toe 4⁴ will lie within the cavity 6 and support the extension 8 upon it, the latter being thus held elevated until such time as a coupling is made whereupon the companion jaw, not shown, in swinging the knuckle 4 will carry the toe 4⁴ beneath the extension 8 and finally engage behind the extension 9, the member 5, 8, 9 dropping to its normal locking position.

A point of advantage in my structure is that since the locking member is guided in its vertical movements vertically by walls surrounding it practically on every side and, further, that the foot 9' thereof is dropped into the socket 10 which presents a front wall thereto rearward of and below the level of the bottom of the cavity 3, that member is wholly and firmly resistant to pulls imposed upon the knuckle 4 and therefore cannot be unseated by the most vigorous pull. Even though the pin 15 that holds the knuckle may be lacking so that the strain is transferred to the said member yet that member can wholly withstand such forces. The engagement of the toe 4⁴ with the extension 9 is positive and no amount of pull upon the jaw 4' can possibly cause separation due to the securing of the portion 4³ between the said extension 9 and its companion extension 8. On the other hand, the means of effecting the release of the jaw is simple, and easy of operation, there being sufficient leverage provided by the lever to lift the said member 5, 8, 9 and throw out the knuckle.

The knuckle itself is believed to be of novel form and quite simple, there being no projections or angles likely to present difficulties in the coupling and uncoupling acts.

The one-piece locking member 5, 8, 9 lies entirely in one plane and besides the fact that its upper portion is guided in the cavity 6, Figure 6, in the top of the coupling, as shown in Figure 2, its portion 8 lies against the rear wall of the coupler-head 1 and is guided its entire length thereby and must always maintain an upright position. That is to say, it cannot swing at its lower extremity in a rearward direction while raised in the uncoupled position of the knuckle. Due also to the fact that the foot-portion 9' lies in the socket 10 the said member since a rigid structure throughout is prevented from moving either in a forward or rearward direction when in the lowered position, being therefore free from any such

movements in any of its positions. These movements are further prevented by the abutment provided at each side of the portion 9 where it lies in the cavity in the vertical wall of the head wherein the knuckle is pivoted—see Figure 1. This control of the member in any and all positions is important in that there can be no misplacement thereof at any time, particularly when a coupling is being made. Of importance, also, is the fact that since there is engagement of but one part of the knuckle behind the locking member necessary to complete the coupling act. In other words it is only necessary for the single toe 4⁴ to engage behind a portion of the locking member, Figure 1, the dropping of the portion 8 behind the portion 4³ of said knuckle preventing the movement of said toe from its locking position. A coupling is produced by the structure named wherein the locking member is held from movement in any direction except a vertical one, and the knuckle by having engagement at the toe point only behind the locking member will be locked without fail at each coupling operation since said locking member is always in its proper position to perform its service.

I claim:

1. In a coupler, a coupler-head including its usual open front cavity, there being a second cavity extending down through the top of the coupler-head opening into the first said cavity, a knuckle mounted in the head whose tail is adapted to swing through the said first cavity into the second said cavity, an inverted substantially flat U-shaped locking member rigid throughout slidably vertically in the said second cavity, the vertical walls of the latter engaging one of the extensions of the member at its front and rear sides, the tail of the knuckle adapted to engage behind part of the rear surface of the said extension, the other of the extensions engaging behind the tail of the knuckle at the guard arm side of the knuckle holding the same in the described engagement with the first described extension, said other extension abutting the rear wall of the said second cavity and guided thereby in the vertical movement imparted to it.

2. In the coupler described in claim 1, a knuckle having an inclined lower surface, and adapted to cooperate therewith a cam rigidly formed on one of the extensions of the locking member.

In testimony whereof I affix my signature.

JOHN H. TAYLOR.
